UNITED STATES PATENT OFFICE

FRANK STANLEY SCHADE, OF HOLYOKE, MASSACHUSETTS, ASSIGNOR TO CHAIN BELT COMPANY, OF MILWAUKEE, WISCONSIN, A CORPORATION OF WISCONSIN

CONVEYER FLIGHT

Application filed October 14, 1926. Serial No. 141,606.

This invention relates to conveyer flights and more particularly to a flight especially adapted for use in connection with a uniplaner type of conveyer such, for example, as that shown in the patent to Levalley 1,028,751 wherein the chain is operated with the chain pins in a vertical plane about sprockets arranged in a horizontal plane and in which the flights are attached to the chain at right angles to the side bars and operate in a horizontal plane.

The invention has for one of its objects to provide a flight for this type of conveyer which will be simple in construction, comparatively inexpensive to manufacture and more efficient in use than those which have been heretofore proposed.

A further object of the invention is to provide a conveyer flight of the class described which may be readily stamped from sheet metal and which may be readily assembled in operative position on any one of several types of standard conveyer chains.

A still further object of the invention is to provide a flight for uniplaner conveyer which will present a substantially unbroken surface for receiving the articles to be conveyed and which is securely fastened to the chain by means of the chain pins.

With the above and other objects in view which will appear as the description proceeds, the invention consists in the novel details of construction and combinations of parts more fully hereinafter described and particularly pointed out in the appended claims.

Referring to the accompanying drawings forming a part of this specification in which like reference characters designate like parts in all the views:

Figure 1 is a plan view of a portion of a uniplaner conveyer with several flights, constructed in accordance with the present invention attached thereto;

Fig. 2 is a central vertical sectional view of the parts shown in Fig. 1;

Fig. 3 is a plan view of a slightly modified form of flight; and,

Fig. 4 is an edge elevational view of the flight shown in Fig. 3.

Referring more particularly to Figs. 1 and

2, there is illustrated a well known form of conveyer chain comprising a plurality of links 5 which are pivotally secured together by means of the chain pins 6 which extend through the cross bars 7 of one link and the ends of the side bars 8 of the next adjacent link in the well known manner. Since no particular novelty resides in the chain it is not thought necessary to describe it more in detail.

Secured to the conveyer chain at each of its articulating centers, as defined by the chain pins 6, are the conveyer flights 10 which constitute the gist of the present invention. As will be clear from Fig. 1, these flights comprise crescent shaped sheet metal members, the edges of which are defined by the arcs 11 and 12, the former of which is struck from the center or chain pin of the link above which the flight is located with a radius approximately equal to the pitch of the chain or preferably slightly less in order to provide clearance. The second arc 12 is struck from the next succeeding center or pin 6 with a radius substantially equal or slightly in excess of the pitch of the chain as will be readily understood.

As above stated and as will be clear from the drawings, the said flights are formed of sheet metal and in order to prevent the heads 13 of the pins 6 from projecting above the upper surfaces of the flights, the latter are provided substantially at their mid portion with a depressed pocket 14, the bottom wall 17 of which is provided with an aperture 15 through which the chain pin 6 may pass before it is riveted or headed, as indicated at 13. The said depressions 14 are preferably formed by stamping and may be substantially rectangular in shape as shown with the ribs 16 or corrugations 16 also formed during the stamping operation extending from the corners of the depressions and serving to strengthen the flight.

The bottom wall 17 of the depressed portions 14 is also provided during the stamping operation with a pair of oppositely extending tongues 18 which as the flight is assembled upon the chain, are bent downwardly to embrace the sides of the chain links to pre-

vent any relative turning movement between the flight and the link.

In order to facilitate the heading or riveting the chain bolts 6 where such bolts are employed, or to permit of the use of a nut where a threaded bolt is employed, the flights are preferably cut away along the outer arcs 11, as indicated at 20 whereby the entire bolt head 13 will be exposed. As a matter of fact, it is possible to assemble a conveyer of this type by employing the present flight without so cutting away the flights except in the case of the last one, but in order to make the flights uniform and lower production costs, it is deemed advisable to cut them all away as indicated in Fig. 1 of the drawings.

When employing a chain using headed bolts such as 6, in order to attach the ends of the chain together, it is customary to employ a threaded bolt 21 as shown in Figs. 1 and 2, which bolt receives the nut 22 to retain the parts in place. In order to lock the said nut against unintentional displacement, a small lug 23 may be formed upon the bottom portion 17 of the depression 14 which lug may be turned upwards as indicated in Figs. 1 and 2 after the parts have been assembled.

In many instances the conveyer may be used with the flights as shown in Figs. 1 and 2 but in some cases the depressions 14 formed in the flights as well as the reentrant arcs 20 may be detrimental in that the articles carried may tend to catch therein. In this event a smooth surface may be provided by attaching to the flights 10, a crescent shaped plate 25 as shown in Figs. 3 and 4, which plate is imperforate except for a pair of small apertures to accommodate the rivets, bolts or other fastening means 26, by means of which said plate is secured to the flight. In some instances it may also be necessary or desirable to provide the flights with upstanding lugs or projections to engage the sides of the articles carried thereby although in ordinary practice this will not be found necessary. In some exceptional instances it may also be necessary to provide brackets to carry rollers or casters, which brackets are attached to the undersides of a portion or all of the various flights 10 to reduce friction and wear upon the said flights.

It will thus be seen that the present invention provides a conveyer flight particularly adapted for use with a uniplaner conveyer which may be operated about sprockets of small diameter without leaving any gaps or openings between the flights. Furthermore the said flights are rigidly connected to the chain by means of the chain bolts and provision is made whereby the flights are prevented from turning relatively to the chain links.

It is obvious that those skilled in the art may vary the details of construction as well

as the precise arrangements of parts without departing from the spirit of the invention and therefore, it is not wished to be limited to the above disclosure except as may be required by the claims.

What is claimed is:

1. In a conveyer of the class described, a conveyer chain; a horizontally disposed flight having a depressed portion engaging and secured to each of the chain links; and means comprising link-engaging tongues for preventing rotary movement of said flight relative to its link.

2. In a conveyer of the class described, a conveyer chain; a horizontally disposed flight having a depressed portion engaging each of the chain links at its articulating center; a bolt carried by said links, passing through said depressed portion; a nut on said bolt, securing said flight to said links; and means carried by said flight for locking said nut against unintentional displacement.

3. In a conveyer of the class described, a conveyer chain; a horizontally disposed flight having a depressed portion engaging each of the chain links at its articulating center; a pair of angularly disposed link-engaging tongues carried by said flight for preventing rotary movement thereof relative to its link; a bolt carried by said links, passing through said depressed portion; a nut on said bolt, securing said flight to said links; and means comprising a lug carried by said flight for locking said nut against unintentional displacement.

4. A conveyer flight comprising a substantially flat sheet metal plate, stamped to provide a depressed chain-engaging portion and reinforcing corrugations extending from said depressed portion.

5. A conveyer flight comprising a substantially flat sheet metal plate provided with a depressed chain-engaging portion having tongues adapted to embrace a portion of a chain link.

6. A conveyer flight comprising a substantially flat sheet metal plate provided with a depressed chain-engaging portion having tongues adapted to embrace a portion of a chain link, said portion being also provided with a nut engaging lug.

7. A conveyer flight comprising a metal base plate provided with a depressed chain engaging portion and a cutaway portion; and a flat cover plate secured to said base plate and concealing said depression and cutaway portion.
